UNITED STATES PATENT OFFICE.

WILLIAM W. ROBERTSON, OF BENTON, MISSOURI.

TOBACCO-PIPE.

No. 839,207.

Specification of Letters Patent.

Patented Dec. 25, 1906.

Application filed July 27, 1906. Serial No. 328,110.

To all whom it may concern:

Be it known that I, WILLIAM W. ROBERTSON, a citizen of the United States, residing at Benton, in the county of Scott and State 5 of Missouri, have invented a new and useful Tobacco-Pipe, of which the following is a specification.

This invention relates to a tobacco-pipe, cigar-holder, or the like of that type having 10 a valve for controlling the smoke-passage, so that smoke can be readily drawn through the passage without the danger of saliva entering the same through the mouthpiece, thereby maintaining the passage dry and 15 clean and preventing the accumulation of nicotin therein.

The invention has for one of its objects to provide a stem for a pipe or cigar-holder provided with a valve which will automatically 20 open under the inhalation of the smoker to permit a draft of smoke through the smoke-passage and automatically close when the suction or inhalation ceases and a means whereby the valve can be held open, so that 25 a puff of air can be blown through the smoke-passage by the smoker for cleaning the same from clogging material.

A further object of the invention is the employment in connection with a stem of this 30 character of a saliva-chamber in which the saliva that may flow in through the passage of the mouthpiece will collect and from which the saliva can be blown out through a normally plugged opening.

Another object of the invention is to provide a device normally contained in the smoke-passage in contact with the wall thereof so arranged that it may be reciprocated for the purpose of loosening any matter that 40 might collect on the wall of the passage, and thus facilitate the cleaning out of the passage by the current of air blown through the same by the smoker; and a further object is to provide a bowl for a pipe and a casing 45 therefor in which the bowl is removably supported, thereby permitting the bowl to be renewed when desired.

With these objects in view and others, as will appear as the nature of the invention is 50 better understood, the invention comprises the various novel features of construction and arrangement of parts, which will be more fully described hereinafter and set forth with particularity in the claims appended hereto.

55 In the accompanying drawings, which

illustrate an embodiment of the invention; Figure 1 is a longitudinal section of a pipe. Fig. 2 is an enlarged detail sectional view of the pipe-stem. Fig. 3 is a transverse section on line 3-3, Fig. 2. Fig. 4 is a perspective view of the pipe-bowl. Fig. 5 is a longitudinal section of an attachment-socket to be used in connection with the stem as a cigar-holder. Fig. 6 is a similar view of a coupling-plug for attachment with the stem to adapt the latter to cob and similar pipe bowls.

Corresponding parts in the several figures are indicated throughout by similar characters of reference.

Referring to the drawings, 1 designates the bowl-section of a pipe, 2 the stem-section, and 3 the mouthpiece. The bowl-section 1 comprises a bowl proper, 4, which is preferably molded or cast of any suitable material, such as aluminium, and formed with a tubular neck 5, that forms part of the smoke-passage communicating with the interior of the bowl. The end of the neck 5 is enlarged at 6 and internally threaded, so as to receive the threaded end 7 of the pipe-stem.

Around the bowl and neck thereof is a casing 8, which may be and preferably is made of sheet-aluminium formed into the desired shape and, if desired, embossed with any suitable ornamentation. The top of the casing is formed with a flange 9, extending inwardly, so as to embrace the upper end of the bowl, the said end and flange being flush, so as to produce a smooth finish. The part of the bowl-casing at the enlargement 6 is provided with an inwardly-extending flange 10, against which the end surface of the enlargement 6 abuts. The bowl is removably held in the casing by means of a spring-latch 11, secured to the bowl, preferably at the exterior thereof. The free end of the latch is offset, so as to produce a recess 12, that engages over the flange 9 of the casing. The casing is preferably spaced apart from the bowl at such a distance as to provide an ample dead-air space, so that the casing may be kept relatively cool.

The stem 2 of the pipe is suitably formed of metal or other material, but preferably of aluminium, so as to comprise a tubular body 13 and a central tube 14, integrally connected with the body 13 at one end by the wall or head 15, said tube forming the main portion of the smoke-passage. The tube 14 and body 13 are suitably spaced apart, so as to

form a spittle or saliva chamber 16. The bore of the tube 14 aligns with the bore of the neck 5 of the bowl, and the end of the tube 14 opposite from the bowl is provided with a conical valve-seat 17, on which seats the ball-valve 18 for controlling communication between the smoke-passage and the passage 19 of the mouthpiece 3. In the wall of the chamber 16, preferably at the top side of the body 14, is an opening 20, normally closed by a stopper or threaded plug 21 and through which the chamber 16 is drained of saliva. The mouthpiece 3 is of the usual construction and may be made of amber, horn, or other suitable material, and preferably curved in the form shown when used for a pipe. When the stem is to be used as a cigar-holder, a straight mouthpiece will be more satisfactory. The end of the body 13 to which the mouthpiece is attached is preferably internally threaded to the proper size, so that mouthpieces of standard manufacture may be employed.

The valve 18 is normally held on its seat by a helical compression-spring 22, that passes into the valve at one end and rests on the inner surface of the mouthpiece at its opposite end. The spring is held in place by extending one terminal thereof into the passage 19 of the mouthpiece. If desired, the spring may be passed through the valve and into the smoke-passage, where it is preferably coiled, as indicated at 23, so that the convolutions will engage the wall of the smoke-passage. The spring 22 and the coil 23 will be of sufficiently light tension that the valve will readily unseat under the suction produced by the smoker. Adjacent the valve is arranged a device for holding the latter off its seat when it is desired to blow out the smoke-passage. This device comprises a shaft 24, mounted in a bearing 25, secured to the body 13, and a finger 26 at the inner end of the shaft, that engages one of the convolutions of the spring 22, so that as the shaft is rocked in one direction the spring can be compressed and the valve drawn off its seat. The shaft 24 extends outside of the pipe-stem and is provided with a crank 27, whereby it is rocked. This device for unseating the valve is a comparatively insignificant structure, so that its weight and friction does not materially affect the automatic opening of the valve under the suction produced by the smoker. Since the coil 23 is positively connected with the valve, it is obvious that by rocking the crank 27 back and forth a number of times the material on the wall of the smoke-passage can be loosened, so that when a puff of air is forced through the smoke-passage the material can be blown out through the bowl.

In order to adapt the stem for use as a cigar-holder, the attachment shown in Fig. 5 is employed. This comprises a body 28,

that is bored at one end at 29 and tapped, so as to screw on the threaded stub portion 7 of the stem. The opposite end of the body is provided with a tapering socket 30 for the reception of the cigar. It may also be desirable to use the stem in connection with a cob or other pipe that is not provided with or internally-threaded socket for receiving the stub portion 7. For this purpose a frustoconical coupling attachment, such as shown in Fig. 6, is employed. This comprises a body 31, that is bored and threaded at one end, as indicated at 32, for receiving the portion 7 of the stem. Extending from the tapped bore 32 is a central passage 33, that communicates with the bowl of the pipe.

From the foregoing description, taken in connection with the accompanying drawings, the advantages of the construction and of the method of operation will be readily appreciated by those skilled in the art to which the invention appertains.

In operation the valve 18 will automatically unseat to permit the puffs of smoke to be drawn through the smoke-passage and to automatically return to its seat when the draft for each puff ceases, thereby effectively preventing moisture or saliva from entering the smoke-passage of the stem. Any saliva that passes inwardly through the mouthpiece collects in the chamber 16, from which it can be readily ejected by removing the plug 21 and turning the pipe over, so that the drain-opening 20 will be lowermost. When in this position, the smoker discharges a strong puff of air through the passage 19 of the mouthpiece and the chamber 16, so as to carry out of the latter the saliva which it contains. It will be noted that during this operation the valve 18 will be permanently held on its seat, so that no saliva can be blown into the smoke-passage. If the smoke-passage should become clogged with ashes or other material, the valve 18 will be held open by turning the crank 27 rearwardly, and then a strong current of air is blown through the pipe, thus clearing out the passage, it being of course understood that the plug 21 will have been first inserted in the opening 20.

I have described the principle of operation of the invention, together with the apparatus which I now consider to be the best embodiment thereof; but I desire to have it understood that the apparatus shown is merely illustrative and that various changes may be made when desired as are within the scope of the invention.

What is claimed is—

1. A smoking-pipe comprising a bowl having a neck provided with an angular enlargement, a metallic casing surrounding the bowl and having a portion fitted to the said enlargement, means for removably holding the bowl in the casing, and a stem connected

with the enlargement of the bowl and coöperating with the said means to hold the bowl firmly in place.

2. In a smoking-pipe, the combination of 5 a bowl, a stem connected therewith, a reciprocatory device arranged in the passage of the stem for scraping loose the particles collected in the passage, a valve at the end of the stem which automatically opens by suction; and a means manually operated from a point exterior to the stem for holding the valve open whereby the particles loosened by the said device can be blown out through the bowl.

15 3. A smoking-pipe comprising a metallic bowl having a neck and an internally-threaded enlargement, a casing for the bowl, a spring-latch for holding the bowl in the casing, and a stem connected with the said enlargement.

20 4. In a smoking-pipe, the combination of a stem having a smoke-passage and a chamber, a mouthpiece connected with the stem and communicating with the chamber, a 25 valve controlling the smoke-passage, a spring between the valve and the mouthpiece and abutting the latter for normally holding the valve seated, and a drainage means for the said chamber arranged to permit a current. 30 of air to be blown successively through the mouthpiece and chamber for cleaning the latter.

35 5. In a smoking-pipe, the combination of a stem having a smoke-passage and a spittle-chamber, a mouthpiece connected with the stem, a valve arranged to control the smoke-passage, means for holding the valve open, and a cleaning device permanently mounted in the stem and operated by the said means.

6. In a smoking-pipe, the combination of 40 a stem having a smoke-passage and a spittle-chamber, a mouthpiece connected with the stem, a valve arranged to control the smoke-passage, and means extending from a point within to a point exterior to the said chamber 45 for holding the said valve open.

7. In a smoking-pipe, the combination of a stem having a smoke-passage and a spittle-chamber, a valve arranged to open by the suction through the stem and to automatically close to control the smoke-passage, a 50 cleaning device extending into the passage and connected with the valve, and means for moving the said device back and forth.

8. In a smoking-pipe, the combination of 55 a stem having a smoke-passage and a spittle-chamber, means for draining the chamber, a valve arranged to control the smoke-passage, a spring for seating the valve, a shaft mounted in the stem, a finger on the shaft engaging 60 the spring to open the valve, and a device connected with the shaft and located exterior to the stem for actuating the former.

9. In a smoking-pipe, the combination of 65 a bowl having an internally-threaded portion, a casing surrounding the bowl and having an internally-extending flange which the threaded portion abuts, and a stem having a reduced threaded portion which screws into the said portion of the bowl to hold the casing and bowl together.

In testimony that I claim the foregoing as my own I have hereto affixed my signature in the presence of two witnesses.

WILLIAM W. ROBERTSON.
